UNITED STATES PATENT OFFICE.

JOSEPH B. NEFF, OF CUBA, ASSIGNOR TO REUBEN ELWOOD, OF SYCAMORE, ILLINOIS.

SULKY-PLOW.

SPECIFICATION forming part of Letters Patent No. 224,034, dated February 3, 1880.

Application filed December 16, 1878.

To all whom it may concern:

Be it known that I, JOSEPH B. NEFF, of Cuba, Fulton county, State of Illinois, have invented new and useful Improvements in SULKY-Plows, of which the following is a full description, reference being had to the accompanying drawings, in which—

Figure 1 is a top or plan view; Fig. 2, a side elevation with a wheel removed; Fig. 3, a cross-section on line *x x* of Fig. 1, with the wheels removed; Fig. 4, a cross-section on line *y y* of Fig. 1; Fig. 5 a side view, and Fig. 6 a front view, of the clevis and its attachments.

The nature of this invention consists in making the connections between the plow-beam and the frame so that the plow may rise and fall freely within the limits furnished; in an improved method of raising the plow; in improved means for attaching the team, and in the several new combinations hereinafter described and claimed.

In the drawings, A indicates the upper portion of the frame, which may be a bent axle; B, the wheels; C, the bent rock-shaft; D, the plow-beam; E, the plow; F, a bar attached to the frame for attaching and supporting the tongue; G, the tongue; H, a foot rest or board; I, driver's seat and its support; J K, hand-levers; L M, notched or toothed segments; N, arms extending forward from the bar A; O, a cross rod or bar upon which the front end of the plow-beam rests; P, a bar or brace connecting the front end of one of the arms N with the bar F; Q, the clevis; a, swinging or loose rods depending from the rock-shaft C; b, a thimble or collar for keeping the rods a in place; c, brackets fastened to the sides of the plow-beam through which the rods a pass; d, collars provided with set-screws e, attached to the rods a and located within the brackets c, for limiting the movement of the plow-beam upon said rods; f, rods and pawls for locking the levers J K in position on the notched segments; g, a band or rod loop at the front end of the bar F, for holding the tongue in place and limiting its vertical movements; h, a bracket, also located on the bar F, for holding the rear end of the tongue, which is more fully described in another application of even date herewith; i, bolts by which the foot-board is attached to the

plow-beam, and by which the beam is attached to the plate or bracket connecting it with the rod or bar O; j, clamp ball or collar with set-screw, by means of which the position of the plow-beam on the rod or bar O is adjusted and held in place; k, plate or bracket provided with ears or bearings, for connecting the front end of the plow-beam with the cross-bar O; m, a secondary clevis; n, a movable and adjustable double-tree or evener support; o p, clevis-bolts; q, a brace-bar forming a portion of the frame A; r, a link attached to the lever K, and s a slide or movable block, to which the spindle B" is attached.

The bar F and the tongue are made of wood, and the other parts are, by preference, of metal; but some of the parts may be made of wood.

The frame or bent-axle portion A is made of a suitable height above the wheel-spindles B', and the arms N are either made of the same bent bar or are permanently attached to it.

The wheel-spindles B' B" may be made partly of cast-iron, and B' is bolted or otherwise fastened to the frame A. The spindle B" is attached to a block, s, which has a vertical movement on the frame A, and is secured thereto by being made in a dovetail form, so as to slide up and down in a groove fitted to the form of the bar; or it may be attached by bent bars fitting over it, united or bolted to the frame A.

The block s is connected with the lever K by a link, r, by means of which and the lever K the spindle B" may be raised or lowered to adjust the height of the tread of the wheels or to level the plow.

At the proper height above the tread of the wheels there is journaled to or through the frame A a bent rock-shaft, C, at one end of which there is attached, by means of the casting J' or otherwise, a lever, J, by means of which the shaft is rocked, whereby the bent portion is raised or lowered.

The lever J is held in position by its pawl acting on the notched segment L. The bent portion of the shaft C extends nearly or quite the distance between the vertical portions of the frame A, and on the bent portion there are two rods, a, suspended or pivoted so as to allow them to turn freely. These bolts a are

held from spreading by the brackets *c*, and are kept in position on the shaft by the collar *b*, which is provided with a set-screw, so that the position of the rods *a* lengthwise the shaft 5 may be adjusted.

The brackets *c* are fastened to the plow-beam *D*, and the rods *a* pass through them. Between the arms of each of these brackets is placed a short collar or button, *d*, which is held 10 in place by a set-screw, and which allows within the limits of the bracket a free vertical play of the plow-beam, so that the plow *E* may play freely up and down while the shaft *C* is held in place by the lever *J*.

15 The bent rock-shaft is raised and lowered to any desired position by the lever *J*, and it is held in place by the rack or segment *L*, and by rocking the shaft *C* up high enough the plow *E* is thrown out of the ground when desired.

20 The front ends of the arms *M* are connected together by the rod or shaft *O*, and to this shaft the front end of the plow-beam is attached so that it can turn by means of the plate *k*, having ears *l*, which plate is attached to the plow-beam by means of the cross-plate, to which the 25 foot-rest is fastened, and the bolts *i*. By loosening the bolts *i* the plate *k* may be adjusted along the plow-beam so as to bring and hold the brackets *c* in their proper position.

30 The front end of the plow-beam is adjusted laterally or along the rod *O* by means of the collar *j*, which is provided with a set-screw, and does not fill the space between the ears or bearings *l*, so that the front end of the plow-beam 35 has a little free lateral play.

The clevis *Q* is made of two plates, or with a vertical opening in front, and is provided with a secondary or cross clevis, *m*, which is held in place by the bolt *p*. The clevis is also 40 provided with a double-tree and evener support, *n*, which is held in place by the bolt *o*. Its back rests against the bolt *p*, which causes it to project so as to support the evener. This supporter can be adjusted up and down by 45 shifting the bolt into different holes, either with or without shifting the position of the cross-clevis. It may be held on the bolt *p* and its upper bent end pass behind the bolt *o*, in which case it will always be adjusted with the 50 cross-clevis *m*.

The foot-board *H* is supported upon the beam by means of one or more bent arms, and by the further bending or straightening of them its height may be regulated.

The bar *F* is supported by the frame *A* and brace *g*, and, as shown, it extends far enough back to furnish a support for the rear end of the segment *L*. Its front end is supported by the brace or bar *P*, which is provided with a series of holes, so that the height of the bar *F*, 60 and through that the height of the tongue, can be adjusted to suit teams of different heights, and to adjust the height of the rod *O* and front end of the plow-beam in reference to the tongue or ground. 65

The rear end of the tongue is pivoted in the bracket *h*, and it is kept in position laterally by the band *g*, in which it has some free play vertically. The wheels and parts mounted thereon are drawn by the bar *o*. 70

The operation will be apparent from the description.

What I claim as new, and desire to secure by Letters Patent, is—

1. The combination of the brackets *c*, attached to the plow-beam, with the rods *a* and adjustable collars *d*, for allowing the brackets a limited free play on the rods, substantially as described. 75

2. The combination of the brackets *c*, rods *a*, and adjustable collars *d* with the collar *b* and rock-shaft *C*, substantially as set forth. 80

3. The plate *k*, having the ears *l*, in combination with the beam *D* and bar or rod *O*, substantially as described. 85

4. The extended bar *n*, for supporting an evener independently of its clevis-support, constructed and applied substantially as specified. 90

5. The combination of the bent axel or frame *A*, arms *N*, rod *O*, adjusting-bar *P*, and bar *F* with the cranked or bent rock-shaft *C*, lever *J*, one or more rods, *a*, one or more brackets, *c*, and plow-beam *D*, all constructed and operating substantially as specified.

JOSEPH B. NEFF.
